UNITED STATES PATENT OFFICE.

MARGARET E. HAMILL, OF FOSTORIA, OHIO, ASSIGNOR, BY MESNE ASSIGNMENTS, TO THE F. VAN BUSKIRK COMPANY, OF CLEVELAND, OHIO, A CORPORATION OF OHIO.

MOISTENER OR SOFTENER FOR WALL-PAPER, PAINT, &c.

No. 827,864.

Specification of Letters Patent.

Patented Aug. 7, 1906.

Application filed August 19, 1904. Renewed February 20, 1906. Serial No. 302,050.

To all whom it may concern:

Be it known that I, MARGARET E. HAMILL, a citizen of the United States, residing at Fostoria, in the county of Seneca and State of Ohio, have invented new and useful Improvements in Moisteners or Softeners for Wall-Paper, Paint, &c., of which the following is a specification.

This invention is a device for removing wall-paper, paint, and the like by the application thereto of steam, and comprises particularly a box or receptacle to which steam is supplied from any suitable boiler, which box is applied to or pressed against the wall or structure to moisten or loosen the paper, paint, or other substance thereon.

It is characterized especially by a flexible edge which fits tightly against the surface, and thereby confines thereto the steam or vapor and also the heat.

The device is illustrated in the accompanying drawings, in which—

Figure 1 is a perspective view thereof. Fig. 2 is a sectional detail in perspective. Fig. 3 is a perspective of a modification suitable for use upon curved walls or surfaces.

The device consists of a box or casing, the edge of which is indicated at 1 and the sides of which are indicated at 2. This is shown 30 rectangular in shape, but may be made any shape desired. The box is bottomless or open on the under side and is provided with a handle 5, whereby it may be manipulated, and with a steam-supply hose 7, which opens 35 into the box through a nipple 6.

The sides 2 are made double or of two spaced walls, as clearly shown in Fig. 2, and the metal forming the walls is turned over or beaded, as at 3, to avoid a sharp edge. Held

between the walls 2 and projecting beyond 40 the same is a strip 4 of flexible material—such as rubber, felt, or the like—and in use this flexible edge fits against the surface to which the box is applied, conforming to any inequalities thereof, and confines the steam and 45 heat to the space directly under the box, preventing the objectionable escape of steam which would occur with a rigid or loosely-fitting edge.

The construction of the modification shown 50 in Fig. 3 is similar in all essential respects, except that the box is curved to conform to curved walls and the like.

In use steam is supplied to the box from any suitable boiler, and the box being pressed 55 against the wall the heat and moisture loosen the paint or the adhesive by which paper is attached to the wall and effects or permits the easy removal thereof and it will be readily understood that the box is moved about 60 until the whole surface or material is loosened and detached.

What I claim as new, and desire to secure by Letters Patent, is—

A device of the kind stated, comprising a 65 rigid box open on the bottom and having double-walled sides, a vapor-supply tube opening into the box, and a strip of flexible material held between said walls and projecting beyond the edge thereof.

In testimony whereof I have signed my name to this specification in the presence of two subscribing witnesses.

MAGGIE E. HAMILL.
